REPLACEABLE HEEL

Max Mauser, Kansas City, Mo.

Application September 9, 1939, Serial No. 294,160

3 Claims.

(Cl. 36—36)

This invention relates to shoe heels and more particularly to detachable and replaceable heels, and has for its principal object to provide a heel which is quickly and easily removable from and replaceable on the shoe without the use of tools.

Further objects of the invention are to provide for attaching an assembled heel member and plate assembly to a shoe to provide for independently removing the heel member from the plate after attachment; to provide for removably holding the heel member on the shoe by the plate while the plate is secured to the shoe; to provide for engagement of a substantial portion of the area of the heel member for holding said heel member tightly against the plate and shoe; to provide for holding the heel member against longitudinal movement on the plate; to provide a heel member and plate assembly in which normal use tends to force the heel member onto the plate for a tighter fitting assembly; to provide for preventing backward movement of the heel member on the holder; to provide for limiting the longitudinal compression of the heel member, and to provide an interchangeable heel which may be applied, removed and transferred from one shoe to the other to compensate for differences in wear, thereby prolonging the life of the heel.

In accomplishing these and other objects of the invention, as hereinafter pointed out, I have provided improved details of structure, the preferred form of which is illustrated in the accompanying drawing, wherein:

Fig. 1 is a perspective view of a shoe equipped with a heel embodying the features of the present invention.

Fig. 2 is a perspective view of a shoe with the attaching plate fixed thereon and the heel member in disassembled spaced relation.

Fig. 3 is a plan view of the heel member showing the attaching slots therein.

Fig. 4 is a bottom view of the heel portion of the shoe with the attaching plate thereon.

Fig. 5 is a longitudinal section through the heel member and plate on the line 5—5, Fig. 1.

Fig. 6 is a transverse section through the heel member and plate on the line 6—6, Fig. 1.

Fig. 7 is a transverse section through a heel member showing the concaved upper surface before attaching to the plate.

Referring more in detail to the drawing:

1 designates a shoe having a sole 2 terminating in a heel tap 3 at the rear thereof. Attached to the heel tap is a heel assembly 4 including an attaching plate 5 and a heel member 6.

The plate 5 is preferably formed of relatively

thin metal and comprises a flat base 7 provided with a plurality of nail apertures 8 for attaching the plate to the heel tap. The sides of the plate are bent downwardly as at 9 and outwardly as at 10 to form L-shaped guides 11, the lateral projecting flanges 12 of which are adapted to engage the heel, said flanges being progressively wider toward the front of the plate which is of such width that the flanges 12 on the guides are adjacent the edge of the heel in approximately the line of nails used for holding conventional heels in place, as shown in Fig. 4.

Intermediate the guides 11, the plate 5 is provided with a rectangular opening 13, preferably formed by bending split portions of the plate downwardly as at 14 and outwardly as at 15 to form L-shaped guides 16 of less height than the guides 11. The opening terminates short of both ends of the plate to form connecting portions 17 and 18 provided with downwardly projecting stop flanges 19 and 20 integral with the connecting portions at the front and rear edges of the plate respectively.

The heel member 6 is preferably formed of molded rubber, or other suitable material, and of the same peripheral contour as the heel tap 3, the upper surface of the heel being concaved as at 21, as shown in Fig. 7, and further recessed as at 22 to accommodate the thickness of the base of the plate 5. Formed in the heel member are L-shaped grooves 23 and 24 for adapting the heel member to be slipped over the guides 11 and 16 respectively, the horizontal portion of the grooves being arranged in alignment in such a manner that the flanges 25 on the shorter guides 16 draw the central portion of the heel member upwardly, pressing the edge thereof into tight engagement with the edge of the heel tap.

The grooves in the heel member open outwardly relative to the front edge thereof and are of the same shape as the guides and lateral flanges thereon so that said member may be moved forwardly on the guides 11 and 16 in applying same to the plate, said grooves terminating within the body of the heel member adjacent the rear thereof, as shown in Fig. 3, to form an effective stop against progress of the heel member in a direction toward the toe of the shoe beyond the normal registering position of the heel member 6 with the heel tap 3.

The forward edge 26 of the heel member is curved to correspond to the curvature of the heel tap, and is recessed as at 26' for engaging the stop flange 19 on the plate to aid in prevent-

ing longitudinal movement of the heel member on the plate.

Normal wear of the shoes having heels of resilient material causes the heel member to compress and tend to shorten at each step; therefore I have provided additional means for holding the rear portion of the heel member against longitudinal movement or creeping on the plate. This means consists of a transverse slot 27 aligning with the stop flange 20 on the plate when the heel member is in registry with the heel tap. The engagement of the stop 20 in the slot 27 also prevents the heel member from being moved backwardly on the holder. Regardless of the force exerted on front or rear edges of the heel, it is held firmly and locked between the stops 19 and 20.

In order that the heel member and plate may be assembled prior to nailing the plate onto the heel tap, thereby assuring correct registry of the peripheries of the heel member and heel tap, said heel member is provided with holes 28 aligning with the nail apertures 8 in the plate.

In assembling a heel member and plate constructed as described, the grooves 23 and 24 are aligned with the guides 11 and 16 and the heel member moved forwardly thereon by hand without the use of any tools. As the heel member reaches normal seated position on the plate and the front curved edge of said heel engages the stop flange 19, the slot 27 aligns with the stop flange 20 allowing the flanges on the guides to draw the heel into engagement with the plate and the flange 20 into the slot 27, as shown in Fig. 5, thereby positively holding all portions of the heel in their relative positions on the plate and eliminating creeping or excessive compression of the heel material.

The assembled plate and heel member may be applied to the heel tap without disassembling, since the holes 28 in the heel member register with the nail apertures 8 in the plate. The application is performed by the assembly being placed on the heel tap and registered therewith and nails 29 placed in the holes 28 and driven into the heel tap by a punch or the like to secure the heel assembly in place in substantially the same manner as in applying a conventional rubber heel.

When the heel member becomes worn the rear edge thereof may be lifted by hand to release the stop flange 20 from the slot 29, and pressure applied to the front of the heel member will move it from the guides. A new heel member may then be applied to the plate, or if the wearer tends to wear the heels of the pair of shoes unevenly the heel member from one shoe may be transferred to the other shoe to compensate for the wear. It will be noted that once the attaching plate is applied to the shoe it is not necessary to disturb the plate as additional heel members may be assembled thereon and always register with the heel tap.

From the foregoing it is obvious that I have provided an improved detachable heel structure which is of simple, inexpensive construction, and which may be conveniently removed from the shoe or attached thereto by an operator or the wearer of the shoes. Also when such heel members become worn on a particular pair of shoes they may be interchanged from one shoe to the other of the pair, thereby securing a longer life of the heel.

When worn so that they need to be replaced, they may be detached and other similar heel members purchased from stock of retail dealers and placed upon the shoes without the use of expert or skilled help, thus effecting considerable saving to the wearer of shoes provided with my invention.

What I claim and desire to secure by Letters Patent is:

- 10 1. A detachable heel structure including a holder adapted to be permanently secured to the heel tap of footwear, the holder having on each side of and adjacent to the median line thereof downwardly projecting substantially parallel spaced guide members carrying lateral projections, downwardly projecting parallel guide members on the sides of the holder, lateral projections on the last named guide members located adjacent the periphery of the heel tap, 15 downwardly projecting stops at the forward and rear edges of said holder, a detachable heel member provided with grooves spaced to align with the guide members on the holder, said grooves opening outwardly on the forward edge of said heel member and being of a length corresponding substantially to the length of the laterally projecting guides on the holder and terminating short of the rear edge of the heel to form stops 20 cooperating with a recess in the forward edge of the heel member for receiving the stop on the forward edge of the holder for locating the heel member in relation to the heel tap, and means 25 in the heel member engaging the stop at the rear edge of the holder for preventing forward compression of the heel member.

- 30 2. In a detachable heel structure, a holder, inner guide members on the holder having laterally projecting flanges, parallel outer guide members extending downwardly from the sides of the holder, laterally projecting flanges on the outer guide members, the periphery of said flanges substantially conforming to the shape of and being spaced inwardly from the periphery of a heel tap to which the holder is 35 adapted to be permanently secured, a depending stop on the forward edge of the holder in alignment with the forward edge of the heel tap, a shoe heel of resilient material having grooves opening outwardly on the forward edge thereof and adapted for sliding over the flanges of said inner and outer guide members, said heel having a recess, and a depending stop at the rear edge of the holder for engaging in said recess in the heel member to limit compression of said heel member.

- 55 3. In a detachable heel structure, a holder, parallel guide members extending downwardly from the holder, laterally projecting flanges on the guide members, said flanges being progressively wider toward the front of said holder, a stop on the holder in alignment with the forward edge of the heel tap to which the holder is adapted to be secured, a shoe heel of resilient material having grooves conforming in shape to the guides and flanges on the holder and opening outwardly on the forward edge thereof adapted for sliding over the guide members and flanges, said heel having a recess, and a stop at the rear of the holder for engaging in said recess in the heel member to limit compression of said heel member.

MAX MAUSER.
